LINER HANGER AND SETTING TOOL THEREFOR

William H. States, Garden Grove, Calif., assignor to Midway Fishing Tool Co., a corporation of California
Original application Jan. 3, 1961, Ser. No. 80,495. Divided and this application Oct. 12, 1962, Ser. No. 230,799

7 Claims. (Cl. 166—124)

This invention relates to the petroleum production industry and particularly to the hanging of a liner within a well casing.

A primary object of the invention is to provide a simple, inexpensive and reliable liner hanger and associated setting tool wherein said tool is retrievable after said hanger is set within the casing.

Another object is to provide a liner hanger which is suspended on a setting tool from a running-in string, which is designed to be set in the casing by a simple double reversal of the direction of longitudinal movement of the hanger in the casing but which cannot be so set until after a preliminary conditioning of the hanger mechanism which can only be accomplished by a multiple rotation of the setting tool in a given direction, preferably the direction in which the joints of the running-in string are made up. This arrangement allows complete freedom in vertical movement of the hanger during the running-in of the hanger and the liner suspended thereon, by the driller knowing that the hanger cannot be set until after the conditioning step has occurred and by knowing also that by its very nature, this step may only be performed deliberately.

Still another object is to provide such a liner hanger in which not only the conditioning step in the operation of the hanger is accomplished by rotation of the setting tool, but also the step of separating the tool from the hanger following the setting of the latter in the casing.

A further object is to provide such a hanger incorporating a tubular expansive rubber packer and in which expansion of the packer is accomplished by rotation of the tool in sequence with the other aforesaid tasks assigned thereto.

A yet further object of the invention is to provide such a liner hanger and tool for setting the same in which the conditioning step may not be performed excepting with the liner setting on the bottom of the well. This contributes to the driller's assurance that the setting of the hanger will not occur during the lowering of the liner into the well.

This application is a division carved out of copending application Serial No. 80,495, filed January 3, 1961, and covers subject matter disclosed in an antecedent application Serial No. 785,271, filed January 6, 1959, both of the aforesaid applications now being abandoned.

The manner of accomplishing the foregoing objects as well as further objects and advantages will be made manifest in the following description taken in connection with the accompanying drawings, in which

FIGS. 1 and 1a show a preferred embodiment in a liner hanger and setting tool of the present invention while the same is being run into a well casing, the packer of the liner hanger being depicted in FIG. 1, while the balance of the hanger disposed therebelow is shown in FIG. 1a.

FIGS. 2 and 2a are views generally corresponding to FIGS. 1 and 1a but illustrate the liner hanger with a liner suspended thereon as being bottomed in the well with the setting tool in position to condition the slip means thereof for anchoring engagement with the well casing.

FIG. 3 is a fragmentary view in longitudinal section, depicting the slips in a position assumed thereby when they

2

have been conditioned for engagement with the expander for expanding said slips into engagement with the casing.

FIG. 4 is a downward extension of FIG. 3.

FIG. 5 is a transverse sectional view through the upper end of the packer of the liner hanger and through the removable hanger plug and is taken on the line 5—5 of FIG. 2, and on a somewhat enlarged scale.

FIG. 6 is a transverse enlarged sectional view taken on the line 6—6 of FIG. 2 and illustrates the setting tool drive lugs in engagement with drive grooves for manipulating the expander of the invention.

FIG. 7 is a fragmentary enlarged view in transverse section taken on the line 7—7 of FIG. 3.

FIGS. 8 and 8a are composite views illustrating the liner hanger of the invention anchored to the well casing by the slips being expanded against the latter, the setting tool being in position for adding the weight of the running-in string to that of the hanger, thus firming such anchoring.

FIG. 9 is a longitudinal sectional view of the packer of the invention and illustrates the same in packed-off condition and with the setting tool engaged with the packer sleeve drive grooves for effecting such action.

FIG. 10 is an enlarged transverse sectional view taken on the line 10—10 of FIG. 2a through the slip mechanism.

FIG. 11 is an enlarged transverse sectional view taken on the line 11—11 of FIG. 9 and more particularly illustrating the setting tool engaged in the packer sleeve drive grooves.

Referring specifically to the drawings and particularly to FIGS. 1 and 1a, a liner hanger H is there shown as being lowered into a well casing C. The hanger H includes a tubular body generally designated by the numeral 1, which is externally threaded at its upper end and screws into an outer upper tubular member 2 which is internally relieved for a substantial distance upwardly from its lower end and has threads 5 thereabove, into which hanger body 1 screws. An inner tubular member 3 is tightly connected to the upper end portion of member 2 by tapered threads 4. The member 2 has a tapered external slip expanding surface 6 adjacent its lower end. The members 2 and 3, functioning as a unit, are herein-after designated generally as expander E.

The hanger body 1 has suitable annular external grooves for receiving O rings 7 which engage the internally relieved surface 7a on member 2 to form a hydraulic seal between the hanger body and member 2, during relative longitudinal movement between the hanger body and said member, the purpose of which will be made clear hereinafter.

50 A circumferentially spaced series of bowed drag springs 8 are supported at their lower ends on a collar 9 and at their upper ends on a slip mounting ring 10, said collar and ring making a close sliding fit on hanger body 1 and combining with said springs to form a drag device D. Formed integral with the ring 10 and extending upwardly 55 therefrom are parallel leaf springs 10a on the upper ends of which are mounted a series of segmental wickered slips 11.

The collar 9 has a pair of diametrically opposed longitudinal slots 12 and hanger body 1 has two suitably tapped holes for receiving screws 12a so that screw heads 13 thereof will slidably fit in corresponding positions in said two slots 12 to fix upper and lower limits within which drag device D and the slips 11 carried thereby are free 60 to have longitudinal movement relative to said hanger body.

As shown in FIGS. 1a, 2a, 3 and 10, the hanger body 1 has a pair of diametrically opposed recesses 14 into which a correspondingly positioned pair of slips 11 are biased 65 by their supporting springs 10a. This places the upper tips of these two slips in endwise abutment with the lower

end 14' of expander E, for a purpose to be made clear hereinafter.

The tubular member 3 has a packer P mounted thereon, this including a sleeve 15 which is screwed externally onto member 3 in opposed relation to the upper end of the tubular member 2 (FIG. 1). Between the sleeve 15 and the tubular member 2 there is disposed a suitable packer element generally designated 16 which includes a series of axially spaced packer rubbers 17 and intermediate spaces 18 which have a normal or relaxed diameter substantially approximating that of the tubular member 2 and the sleeve 15, but which, upon axial movement of the sleeve 15 towards the member 2, are adapted to be squeezed axially and thereby expanded into engagement with the casing C so as to effect a packed-off condition.

A well liner L is suspended from the lower end of the hanger body 1 as by a simple threaded connection shown in FIGS. 1a and 2a.

For suspending the hanger H while lowering said hanger and the liner L suspended thereon downwardly through the casing C, and for operating the mechanism of the hanger to set the hanger on said well casing, a setting tool T is provided. This tool includes a mandrel 20 having a square cross section which connects with the hanger H through a plug 21 having a square axial opening 22 through which the mandrel 20 extends and which conforms to the cross section of said mandrel whereby said plug may be rotated by the rotation of said mandrel. The plug 21 is provided with a depending skirt 23 which has coarse external left-hand threads 24 which screw into complementary threads provided within an upper portion of the tubular member 3. At its upper end, as shown in FIG. 2, the mandrel 20 is threaded as at 25 for the reception of a top sub 26 which screws onto the lower end of a running-in tubing string 27. At its lower extremity, the mandrel 20 is provided with a lower sub 28 threadedly connected to the mandrel as at 29 and having a lower threaded socket 30 for the reception of a stinger pipe or a washing tool, as may be desired, for performing certain fluid injection operations through the mandrel of the setting tool after the hanger has been set in the casing C, either before or after the annular space between the hanger and the casing has been packed off by the packer P.

Disposed about the mandrel 20 and seating upon the lower sub 28 is a circular plate 31 on which rests a thrust bearing 32. Above the bearing 32 is a thrust washer 33. The lower plate 31, the thrust bearing 32 and the washer 33 are all rotatably mounted on a circular section of the mandrel 20 located between the lower sub 28 and a set-down shoulder 34 provided on the mandrel 20 which, as hereinafter will be more particularly described, serves to set the slips 11 firmly after they have been expanded against the casing C. Above the set-down shoulder 34, the mandrel 20 is provided with a further shoulder 35 forming an upper limit stop for an annular carrier head 36 which is slidably disposed on a circular section of the mandrel 20 between the shoulders 34 and 35. This head 36 has a depending skirt 37 adapted to embrace the bearing 32 and washer 33, as shown in FIG. 1, and engage the bottom plate 31. Inasmuch as it is desired that the head 36 be connected to the mandrel 20 for rotation therewith, the head 36 is keyed to the mandrel 20 as by a key 38 (FIGS. 6 and 11).

Carried by the head 36 is a pair of torque lugs 39 each laterally shiftable in a longitudinally extended radial slot 40 in the carrier head 36 and loaded radially outwardly by coiled springs 41 partially recessed in the torque lugs 39 and bearing against the base of the respective slots 40. Pins 42 extend through radially extended slots 43 in the torque lugs 39 so as to limit outward movement of the lugs.

Torque lugs 39 are adapted for engagement in a pair of diametrically opposed grooves 45 extending longitudinally in the inner surface of a lower portion of mem-

ber 3 of expander E, whereby the expander may be rotated by rotation of the setting tool T. Formed within an upper portion of the sleeve 15 is an additional pair of diametrically opposed torque grooves 46 which constitute packer sleeve drive grooves and the torque lugs 39 engage these grooves during the phase of operation in which the packer P is being set against the casing C.

Operation

The operation of the above described invention begins with the assembly of the same with the parts related as shown in FIGS. 1 and 1a with the upper sub 26 of the setting tool T tightly screwed onto the lower end of a running-in string 27. The tubular body 1 of the hanger H has suspended on the lower end thereof the liner L which it is the purpose of the hanger to support within the casing C at a level selected by the driller. The weight of the liner L and the hanger H are transmitted through the setting tool T to the running-in string through the lower sub 28 mounted on the lower end of the mandrel 29. This weight is transmitted downwardly onto the sub 28 by the plug 21 through the torque head 36, washer 33, thrust bearing 32, and circular plate 31.

With the hanger H and liner L thus suspended on the setting tool T, the latter is lowered on the lower end of the running-in string 27 until the lower end of the liner L comes to rest in the bottom of the well (FIG. 2a). The relief of the running-in string of the weight of the liner and hanger will of course immediately be indicated to the driller causing him to decrease the speed of descent of the running-in string to where he will be able to detect when the downward movement of the tool T, relative to the hanger H, results in the plate 31 coming to rest on the upper end of the hanger body 1 (FIG. 2). Engagement of the shoulder 35 with the torque head 36 carries this head downwardly until the lugs 39 therein are biased outwardly into the vertical torque grooves 45 provided in the lower end portion of tubular member 3 of the expander E. It is to be noted in FIG. 2 that while torque head 36 was shifted downwardly by the engagement of shoulder 35 on mandrel 20 therewith, none of the weight of the mandrel and running-in string is transmitted through this shoulder to said torque head because the mandrel shoulder 34 at this time engages the washer 33 to impose the weight of the mandrel and running-in string 27 through the thrust bearing 32 and circular plate 31 to the hanger body 1.

Whatever weight is transmitted by shoulder 34 to the hanger body 1 at this time, is transmitted through the thrust bearing 32 so that mandrel 20 may be readily rotated by rotation of the running-in string. As all of the joints of the latter are provided with right-hand threads, all of the threads described in the invention excepting those specifically mentioned as being left-hand threads are right-hand threads and rotation of the running-in string 27 is always in a clockwise direction.

FIG. 1a illustrates the invention as it is being lowered through the casing C and shows how the spring arms 8 of the drag device D frictionally engage the inner surface of the well casing C so as to retard downward movement of the drag device thus causing said device to be a slight drag in the downward travel of the hanger H thereby positioning the drag device at the upper of the two limits between which it has freedom to reciprocate vertically on the hanger body 1. The means for setting these limits of reciprocation of the drag device on the hanger body comprise the screw heads 13 and the slots 12 in which said screw heads slidably lie, said heads engaging the lower ends of these slots when the drag device is at its upper limit of reciprocation and the upper ends of said slots when said drag device is at the lower limit of its freedom to reciprocate on hanger body 1.

It is thus seen that when the invention is being lowered through a casing C as shown in FIGS. 1 and 1a, the upper extremities of the wickered slips 11 mounted on the drag device D are spaced just downwardly from the lower edge

14' of the expander E. With the expander E thus spaced upwardly from the slips 11 with the latter in their upward-most positions on the hanger body 1, the setting of said slips against the casing C is a practical impossibility while the device is being lowered through the casing C. The driller in charge of the operation is thus assured that he need not fear the setting of the slips 11 against the casing prematurely because the driller has completely within his control the means for operating the setting tool T to lower the expander E relative to the hanger body 1 to condition the expander E and the slips 11 whereby a simple reversal of vertical movement of the hanger body in the well casing C will result in expanding the slips 11 against the casing C and thus set the hanger H with the liner L suspended therefrom, in said casing C.

The present embodiment of the invention provides an additional safeguard by preventing the conditioning step from taking place until after the liner L has come to rest on the bottom of the well as shown in FIG. 2a. As already described, this permits the lowering of the mandrel 20 through the plug 21 and the positioning of the head 36 by engagement of the shoulder 35 therewith so that the lugs 39 expand outwardly into the grooves 45 of the tubular member 3 of the expander E with the mandrel 20 supported by thrust bearing 32 so as to facilitate rotation of said mandrel.

The driller, noting when the parts of the invention are positioned as shown in FIG. 2 in readiness for the conditioning step to take place, rotates the mandrel 20 through the running-in string 27 in a clockwise direction thereby rotating the expander E and the plug 21 so that threads 5 on tubular member 2 advance the expander downwardly on the hanger body 1 as shown in FIG. 3. This rotation and gradual downward movement of the expander E brings the lower edge of the latter into abutting contact with the upper ends of those slips 11 which are sprung inwardly into external recesses 14 formed in hanger body 1 so that the downward movement of the tubular member 2 is transmitted to the drag device D through said slips thereby shifting said drag device and all the slips 11 embodied therewith a substantial distance downwardly from its upper limit of reciprocable freedom relative to the hanger body 1, as clearly shown in FIG. 4.

The conditioning step just described shifts the expander E downwardly from the potentially inoperative position relative to the slips which it had when being lowered in the well to the potentially operative position it has relative to the slips as shown in FIG. 3, yet, without said expander functioning to expand the slips against the well casing C. As above noted, the latter step in the present invention is always reserved for accomplishment by a simple reversal of longitudinal movement of the hanger body 1 in the casing C after the conditioning step has taken place.

The actual setting step, which remains to be done when the parts are related as shown in FIG. 3, requires the setting tool T to be drawn upwardly to again suspend the hanger H and liner L on said setting tool with the tool related to the hanger as shown in FIG. 1. As the hanger is thus lifted to reverse its downward movement in the well, the drag device D remains in engagement with the well casing until the screw heads 13 engage the upper limits of the slots 12 in the collar 9 whereupon such engagement causes the drag device D to join in the upward travel of the hanger H through the casing C. When the driller has noted the arrival of the hanger H at the level in the well where he desires to set said hanger, he makes another reversal of longitudinal direction of travel of the hanger in the casing C by halting his lifting of the running-in string 27 and starting to lower the latter. When this occurs the drag device D, through its frictional engagement with the casing C remains stationary, while the downward movement of the expander E brings the tapered slip expanding surface 6 into outward wedging relation with all of the slips 11, thereby expanding said slips out-

wardly to bring their outer wickered faces into biting engagement with the inner surface of the well casing C as illustrated in FIG. 8a.

After engagement of the slips 11 with the casing C has taken effect so that said slips support the weight of the hanger H and the liner L on said casing, the downward movement of the mandrel 20 is continued as shown in FIG. 8 until the weight of the mandrel and running-in string is imposed on the upper end of the hanger body 1 so as to ram the expander E downwardly with considerable force within the slips 11 thereby firming the setting of the hanger H in the casing C.

Following the setting of the hanger H in the casing C, as above described, the mandrel 20 is lifted to free lugs 39 from grooves 45, and then rotated in a clockwise direction which rotation is transmitted to the plug 21 thereby causing the latter to unscrew from the upper end of tubular member 3 as shown in FIG. 9. The mandrel 20 is then lifted to bring the torque head 36 opposite the upper portion of the packer sleeve 15 causing the torque lugs 39 to be biased outwardly into vertical torque grooves 46 of said sleeve whereby rotation of the mandrel 20 rotates the sleeve 15 and sets the packer P against the casing C by expanding the packing rubbers 17 against said casing as shown in FIG. 9. This being the final step in the operation of the invention, and leaving the mandrel 20 free, as it does, to be lifted upwardly carrying the torque head 36 and plug 21 thereon, the running-in string 27 is therefore now removed with the setting tool T from the well.

If desired, the setting tool may be retrieved from the well before the packer P is set, and the liner may be cemented, washed or the well otherwise treated, following which the setting tool T may be run back into the upper end of the liner hanger, as shown in FIG. 9, where the torque lugs 39 will engage in the packer torque grooves 46 in the sleeve 15. In this connection it should be noted that the sleeve 15 has a tapered upper surface 15' with which the lower extremities of the torque lugs 39 will engage as the setting tool is being reinserted into the hanger H. This tapered surface 15' will effect a camming action on the torque lugs 39 tending to radially depress them in their slots 40 to the extent necessary to accomplish their reception within the upper end of the sleeve 15. Such engagement will be effected while the setting tool T is being rotated so as to bring the lugs 39 into alignment with the grooves 46 whereupon the lugs will enter these grooves, permitting further downward movement of the setting tool to approximately the position in which this is shown in FIG. 9. Rotation of the setting tool for a sufficient number of turns to set the packer P in the casing C will follow, after which the setting tool will be retrieved from the well.

As shown in FIG. 2, the mandrel 20 has a central passage 20' of the same diameter as the passage provided in the running-in string 27 so as to readily transmit through the mandrel 20 to any wash pipe or the like suspended from the lower end thereof on the sub 28 any instruments or fluid material required in an operation to be conducted within the liner L.

The foregoing description of a preferred embodiment of the invention is believed to make clear how the invention accomplishes all of the objects set forth in the preamble of this specification. While only a single embodiment of the invention has been disclosed, it is to be understood that this is for illustrative purposes only, and that various changes and modifications may be made in this without departing from the spirit of the invention or the scope of the appended claims.

What is claimed is:

1. In a hanger and a tool for setting the same in a well casing to suspend a liner from said casing, the combination of: a tubular hanger body; a drag device mounted on said body and freely reciprocable longitudinally relative to said body between upper and lower limits on said

body, said device frictionally engaging said casing to retard longitudinal movement and rotation of said device in said casing; means on said body and said drag device defining said limits by engaging said device when longitudinal movement of said body relative to said device has brought said device to either of said limits, said limit defining means thereupon causing said device to move longitudinally in said casing with said body; key means limiting relative rotation between said body and said device; slip means provided on said device and extending upwardly therefrom; an expander for said slip means longitudinally shiftably mounted on said body above said slip means and normally disposed upwardly out of operative relation with said slip means when said drag device is at its upper limit aforesaid on said body; a setting tool for suspending said body from the lower end of a running-in string with a well liner suspended on said body, to lower said body and liner into said casing; and threaded means operable through said tool by rotation of said string, to lower said expander relative to said body, and to produce relative vertical movement between said body and said device which lowers said drag device relative to said body a substantial distance below the upper limit of free movement of said device relative to said body, whereby said lowering of said expander relative to said body does not function to expand said slip means but conditions said expander and slip means for expanding the latter against said casing when said body is thereafter lowered relative to said casing.

2. A combination as recited in claim 1 wherein said setting tool is rotatable within said body and said expander comprises an internally threaded sleeve and said body has external threads on which the expander screws; and means on said tool engageable with said expander to rotate the latter relative to said body to shift said expander downwardly on said body as aforesaid.

3. A combination as recited in claim 2 wherein means is provided for transmitting to said drag device said downward movement of said expander on said body, to produce the downward movement aforesaid of said drag device relative to said body.

4. A combination as recited in claim 3 wherein recesses are provided externally in said tubular body so as to be located opposite certain of said slip means when said drag device is at its upper limit of movement on said body, said slip means being spring mounted on said drag device so as to flex inwardly into said recesses and be aligned in endwise abutment with said expander whereby the advancing downward of the latter into its potentially operative position relative to said body pushes the slip means aligned therewith downwardly relative to said body and out of said recesses and thus positions the drag device and slip means in general downwardly relative to said body for accomplishing expansion of the slip means against the casing merely by lowering the body relative to said drag device.

5. In a hanger and a tool for setting the same in a well casing to suspend a liner from said casing, the combination of: a tubular hanger body; a drag device mounted on said body and freely reciprocable longitudinally relative to said body between upper and lower limits on said body, said device frictionally engaging said casing to retard longitudinal movement or rotation of said device in said casing; means on said body defining said limits by engaging said device when longitudinal movement of said body relative to said device has brought said device to either of said limits, said limit defining means thereupon forcing said device to move longitudinally in said casing with said body; key means limiting relative rotation between said body and said device; slip means provided on said device and extending upwardly therefrom; an expander for said slip means comprising a tubular upward extension of said body having internal right-hand threads in a lower por-

tion thereof into which matching external threads on an upper portion of said body screw, said expander having vertical internal torque grooves formed therein above the upper end of said tubular body, and coarse left-hand internal threads within an upper portion thereof; a plug having complementary external left-hand threads screwed downwardly into said expander, said plug having a central polygonal aperture therein; a setting tool including a mandrel provided with means at its upper end for attachment to a running-in string, said mandrel being of polygonal cross section and slidably fitting and extending downwardly through said plug; a head mounted on the lower end of said mandrel to engage said plug and thus support said body and a liner suspended from the latter, on said mandrel, said head being above the level of said torque grooves when thus supporting said body; radially biased lugs on said head adapted to be lowered to the level of said grooves to engage therewith by lowering said mandrel after said liner has been bottomed in said well, thereby relieving said expander of the weight of said liner and hanger body, rotation of said mandrel thereupon rotating said expander to lower the latter relative to said body; and means for transmitting to said drag device said downward movement of said expander on said body to lower said device relative to said body a substantial distance beneath the upper limit of free movement of said device relative to said body, whereby said lowering of said expander relative to said body does not function to expand said slip means but conditions said expander and slip means for producing expansion of the latter against said casing when said body and liner are thereafter lowered relative to said casing after being first lifted from the bottom of the well, said tool being retrievable following the setting of said hanger in the casing by right-hand rotation of said tool thereby unscrewing said plug from said expander.

6. A combination as recited in claim 5 wherein the upper portion of said expander is externally threaded; and an annular rubber packer provided externally on said expander, said packer including an internally threaded sleeve which screws downwardly on said expander, said sleeve having longitudinal torque grooves within an upper portion thereof, said grooves being engageable by said lugs after the unscrewing of said plug from said expander, whereby said packer may be set against said casing by rotation of said mandrel.

7. A combination as recited in claim 5 wherein a lower portion of said mandrel is cylindrical with a reduced diameter thus providing a mandrel supporting shoulder at the upper end of said portion; a sub mounted on the lower end of said mandrel; a circular plate rotatably mounted on said cylindrical portion of said mandrel below said head; thrust bearing means mounted on said portion of said mandrel between said plate and said head; and a second shoulder formed on said mandrel above said first shoulder to propel said head downwardly to the level of said expander torque grooves when said liner is bottomed in said well, said first mentioned shoulder at this time engaging said thrust bearing means to seat said plate on the upper end of said hanger body and rotatably support said mandrel and running-in string on said body and said liner, thereby amply retarding rotation of said body during the expander rotating step while minimizing the friction of rotating said mandrel.
